(57) **CLAIM**

The ornamental design for a bicycle turn signal, as shown and described.

DESCRIPTION

FIG. 1 is a front elevation view of a bicycle turn signal showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a rear isometric in use view thereof; and,

FIG. 7 is a front isometric in use view thereof.

The broken lines shown in FIGS. 6 and 7 are for illustrative purposes only and form no part of the claimed design.
